23,701

SUBSTITUTED PIPERAZINES AND METHOD
OF PREPARING SAME

Hugh Wendell Stewart, Plainfield, N. J., and
Ellen Grant Lee, Amherst, Va., assignors to
American Cyanamid Company, New York, N. Y.,
a corporation of Maine

No Drawing. Original No. 2,520,479, dated Au-
gust 29, 1950, Serial No. 76,853, February 16,
1949. Application for reissue December 31,
1952, Serial No. 329,152

9 Claims. (Cl. 260—268)

Matter enclosed in heavy brackets [ ] appears in the original patent but forms no part of this
reissue specification; matter printed in italics indicates the additions made by reissue.

1

This invention relates to new organic com-
pounds. More particularly it relates to 1-di-
alkylcarbamyl-4-substituted piperazines and
methods of preparing the same.

The 1-dialkylcarbamyl piperazines of the pres-
ent invention may be illustrated by the follow-
ing general formula:

in which R and R' are members of the group
consisting of hydrogen and lower alkyl radicals,
R'' and R''' are hydrogen and aliphatic radicals
and X is a member of the group consisting of
sulfur and imino radicals. In the above formula
the term "lower alkyl" radical means a radical
of 1 to 4 carbon atoms.

In general, the compounds of the present in-
vention are solids varying in color from white
to tan. In some cases the compounds may be
an oil at room temperature. They are, in gen-
eral, slightly soluble in water but readily soluble
in benzene, lower aliphatic alcohols, isopropyl
acetate, and the like. The 1-dialkylcarbamyl-
piperazines, having in the 4-position a guanyl
group (when X in the formula is an imino radi-
cal), are capable of forming water soluble addi-
tion salts.

The preparation of the new compounds of the
present invention may be accomplished in sev-
eral ways, dependent to a large extent on the
nature of the product desired. We prefer to
prepare the compounds by reacting a 1-dialkyl-
carbamylpiperazine, having the formula:

in which R and R' are as defined above or addi-
tion salts of such piperazines with any com-
pound which is capable of introducing into the
4-position of the piperazine nucleus a group rep-
resented by the formula:

in which R'', R''' and X are as previously de-
fined. As starting material we can use com-
pounds such as 1-diethylcarbamylpiperazine;
1-diethylcarbamyl-2,5-dimethylpiperazine; 1-di-

2

methylcarbamylpiperazine; 1-dimethylcar-
bamyl-2-methylpiperazine; 1-dipropylcarbamyl-
piperazine; 1-diisopropylcarbamylpiperazine;
1-dimethylcarbamyl-2,5-dimethylpiperazine;
5 1-diethylcarbamyl-2,5-diethylpiperazine and the
like. The preparation of a number of these com-
pounds is described and claimed in a copending
application, Serial Number 661,884, filed April
12, 1946, now Patent Number 2,467,895, April 19,
1949.

As intermediates to be reacted with the 1-di-
alkylcarbamylpiperazines, or their addition salts,
we can use an [alkali metal thiocyanate or] aliphatic
15 isothiocyanate to produce [1-dialkyl-
carbamyl-4-thiocarbamylpiperazines and] 1-di-
alkylcarbamyl-4-alkyl thiocarbamylpiperazines.
[The conditions for carrying out this reaction
are somewhat dependent upon the starting ma-
terials. In general, the 1-dialkylcarbamyl-4-
20 thiocarbamylpiperazines are readily obtained at
room temperature by the interaction of 1-di-
alkylcarbamylpiperazine hydrochloride in aque-
ous solution with an alkali metal thiocyanate.
However, if the corresponding ring substituted
25 piperazines are desired, they are usually obtained
by heating the intermediates in a fusion proc-
ess.] The reactions of 1-dialkylcarbamylpiper-
azines with aliphatic isothiocyanates are, in
30 general, carried out in organic solvents such
as benzene, isopropyl acetate, dibutyl ether,
toluene, and the like at temperatures from about
20° C. up to the boiling point of the particular
solvent chosen. The 1-dialkylcarbamylpiper-
35 azines can also be reacted with a dialkylthio-
carbamyl chloride to produce 1-dialkylcarbamyl-
4-dialkylthiocarbamylpiperazines.

The 1-dialkylcarbamyl-4-guanyl piperazines
may be prepared from 1-dialkylcarbamylpiper-
azines by the following methods: (1) the re-
40 action of 1-dialkylcarbamylpiperazines, or their
addition salts, with a cyanamide in a solvent
such as water, aqueous alcohol and the like and,
(2) by the reaction of 1-dialkylcarbamylpiper-
azines with an S-alkyl isothiourea salt in a
45 solvent, such as those given immediately above.
It is preferred that these reactions take place
within the temperature range of about 70° C.
to about 110° C., depending upon the solvent
medium chosen. Since these compounds are
50 basic in character due to the presence of the
guanyl group, they will form stable addition salts
on treatment with acid.

The compounds of the present invention are
useful as new pharmaceutical products because
55 of their physiological activities and relatively

low toxicity. Some of the compounds exhibit marked analgesic properties, others are useful because of other properties.

The following examples show in greater detail the preparation of illustrative 1-dialkylcarbamyl-4-substituted piperazine within the scope of the present invention.

EXAMPLE 1

Trans-1-diethylcarbamyl-2,5-dimethyl-4-guanylpirazine acetate

To a solution of 53 parts of trans-1-diethylcarbamyl-2,5-dimethylpiperazines in 23.6 parts of 36% hydrochloric acid is added 67 parts of 24% aqueous cyanamide. The mixture is made acidic to Congo red with hydrochloric acid and refluxed for seven hours. The reaction mixture is saturated with solid potassium carbonate and the trans-1-diethylcarbamyl-2,5-dimethyl-4-guanylpirazine is extracted with acetone. The solvent is removed by evaporation and the free base is dissolved in glacial acetic acid. The acetate salt is obtained by precipitation with absolute ether. The product obtained is trans-1-diethylcarbamyl-2,5-dimethyl-4-guanylpirazine acetate which melts at 208.1°-209.6° C.

EXAMPLE 2

1-diethylcarbamyl-4-guanylpirazine hemisulfate

A slurry of 40 parts of absolute alcohol, 18.5 parts of 1-diethylcarbamylpirazine in 13.9 parts of S-methylthiourea sulfate is refluxed for 14 hours. The reaction mixture is filtered and the filtrate is evaporated. The residue is purified by recrystallization from amyl alcohol and the product obtained is 1-diethylcarbamyl-4-guanylpirazine hemisulfate, having a melting point of 236.0°-240.6° C. with decomposition.

EXAMPLE 3

1-diethylcarbamyl-4-thiocarbamylpirazine

To 21.6 parts of 5 N hydrochloric acid is added 18.5 parts of 1-diethylcarbamylpirazine with cooling. To the mixture is added a solution of 9.7 parts of potassium thiocyanate in 15 parts of water. The reaction mixture is allowed to stand overnight and is then evaporated under reduced pressure on a steam bath. The residue is recrystallized from amyl alcohol. The product, 1-diethylcarbamyl-4-thiocarbamylpirazine, melting at 138.2°-140.0° C. is obtained.

EXAMPLE 4

1-diethylcarbamyl-4-ethylthiocarbamylpirazine

To a solution of 55.6 parts of 1-diethylcarbamylpirazine in 80 parts of benzene is slowly added 26.1 parts of ethyl isothiocyanate. The temperature of the reaction mixture is maintained at 30°-40° C. with cooling. The reaction mixture is then heated at refluxing temperature for 1/2 hour. The product is precipitated from solution by the addition of 100 parts of petroleum ether. The product, 1-diethylcarbamyl-4-ethylthiocarbamylpirazine, when crystallized from a mixture of isopropyl acetate and petroleum ether, melts at 87.5°-88° C.

EXAMPLE 5

Trans-1-diethylcarbamyl-2,5-dimethyl-4-thiocarbamylpirazine

To a solution of 64 parts of trans-1-diethyl-

carbamyl-2,5-dimethylpiperazine in 350 parts of absolute ether is added anhydrous hydrogen chloride until the slurry is acidic to Congo red paper. The crystallized salt is isolated by filtration and dried. It is then ground in a mortar and mixed well with 32 parts of potassium thiocyanate. The mixture is heated at its melting point (120°-130° C.) for 1/2 hour. It is then extracted with 85 parts of boiling isopropyl acetate, and the hot extract is filtered. The filtrate, on cooling, deposits white crystals of trans-1-diethylcarbamyl-2,5-dimethyl-4-thiocarbamylpirazine which melts at 123°-123.5° C.

EXAMPLE 6

1-diethylcarbamyl-4-allylthiocarbamylpirazine

To a solution of 55.6 parts of 1-diethylcarbamylpirazine in 40 parts of benzene is slowly added at 35°-40° C. with cooling and stirring, 29.7 parts of allyl isothiocyanate. The reaction mixture is refluxed for 1/2 hour and the benzene then removed by distillation. The residue is crystallized from 26 parts of isopropyl acetate and 43 parts of petroleum ether. The 1-diethylcarbamyl-4-allylthiocarbamylpirazine melts at 80°-80.5° C.

We claim:

1. Compounds of the group having the general formula:

in which R and R' are members of the group consisting of hydrogen and lower alkyl radicals, R'' and R''' are members of the group consisting of hydrogen and an aliphatic radical of 1 to 4 carbon atoms and X is a member of the group consisting of sulfur and imino radicals, and R'' and R''' are not simultaneously hydrogen when X is sulfur.

2. Compounds having the general formula:

in which R and R' are lower alkyl radicals.

3. Compounds having the general formula:

in which R'' is an aliphatic radical of 1 to 4 carbon atoms and R''' is hydrogen.

4. Compounds having the general formula:

5. Trans-1-diethylcarbamyl-2,5-dimethyl-4-guanylpirazine.

6. 1-diethylcarbamyl-4-thiocarbamylpirazine.

7. 1-diethylcarbamyl-4-ethylthiocarbamylpirazine.

8. A method of preparing compounds having the general formula:

in which R and R' are members of the group consisting of hydrogen and lower alkyl radicals and X is [a member of the group consisting of sulfur and] an imino radical[s] which comprises reacting a compound having the following formula:

in which R and R' are as defined above with [a member of the group consisting of alkali metal thiocyanates,] cyanamide [and thiocarbamyl halides] and recovering the said 1-dialkylcarbamyl-4-substituted piperazine therefrom.

9. A method of preparing compounds having the general formula:

in which R and R' are members of the group consisting of hydrogen and lower alkyl radicals, R'' and R''' are members of the group consisting of hydrogen and an aliphatic radical of 1 to 4 carbon atoms, and R'' and R''' are not simultaneously hydrogen, which comprises reacting a compound having the following formula:

in which R and R' are as defined above with a member of the group consisting of [alkali metal thiocyanates,] alkyl isothiocyanates and dialkylthiocarbamyl halides and recovering the said 1 - dialkylcarbamyl - 4 - thiocarbamylpiperazine therefrom.

10. A method of preparing a 1-dialkylcarbamyl-4-thiocarbamylpiperazine which comprises reacting a 1-dialkylcarbamylpiperazine with an alkali metal thiocyanate in the presence of a solvent and thereafter recovering said 1-dialkylcarbamyl-4-thiocarbamylpiperazine therefrom.]

11. A method of preparing 1-diethylcarbamyl-4-thiocarbamylpiperazine which comprises reacting 1-diethylcarbamylpiperazine with potassium thiocyanate in a substantially aqueous solution and recovering said 1-diethylcarbamyl-4-thiocarbamylpiperazine therefrom.]

12. A method of preparing 1-diethylcarbamyl-4-ethyl-thiocarbamylpiperazine which comprises reacting 1-diethylcarbamylpiperazine with ethyl isothiocyanate in a solvent and recovering said 1-diethylcarbamyl -4- ethylthiocarbamylpiperazine therefrom.

13. A method of preparing trans-1-diethylcarbamyl - 2,5 - dimethyl-4-guanyl piperazine which comprises heating trans-1-diethylcarbamyl-2,5-dimethylpiperazine with cyanamide in a solvent and recovering said trans-1-diethylcarbamyl-2,5-dimethyl-4-guanyl piperazine therefrom.
